COMBINED ARTICLE HOLDER AND SEAT BACK COVER FOR AN AUTOMOBILE

Lyda Blalock Roberts, 1/2 Security Savings & Loan
Association, 128 N. Main St., Farmville, N.C. 27828

Filed Sept. 23, 1966, Ser. No. 3,993

Term of patent 14 years

U.S. Cl. D15—8
Int. Cl. D12—14; D6—01

Fig. 1

FIG. 1 is a perspective view of the back of a combined article holder and seat back cover for an automobile embodying the invention, the view showing principally the back portion of the slip cover.

FIG. 2 is another perspective view of the same, but showing principally the front area of the slip cover.

FIG. 3 is an end elevation of the same, showing the end opposite to the one appearing in FIGS. 1 and 2.

I claim:

The ornamental design for a combined article holder and seat back cover for an automobile, as shown.
